UNITED STATES PATENT OFFICE.

HARRY S. WHEATON, OF DALLAS, IOWA.

AUTOMATIC SAFETY WINDOW LATCH.

Application filed June 6, 1923. Serial No. 643,629.

The object of my invention is to provide a window latch which is automatic in its operation and which can be made cheaply and which will work efficiently.

More particularly, my invention relates to a window latch adapted to be used in combination with a pair of window sashes, which are slidable relative to each other, the latch being of such construction that it will automatically engage one of the sashes for preventing any movement thereof.

Still a further object is to provide a hand engaging element which may be engaged by the hand of the operator, with the thumb engaging a release lever for releasing the latch and permitting the window sashes to be moved relative to each other.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a perspective view of a pair of window sashes with my improved latch shown thereon.

Figure 2 is a central, vertical, sectional view through a pair of window sashes and my latch.

Figure 3 is a detail, sectional view taken on line 3—3 of Figure 1; and

Figure 4 is a detail view showing the pivotal connection between the control lever and the plunger rod.

In the accompanying drawings, I have used the reference numeral 10 to indicate generally a window casing provided with the ordinary divider strip 11. Slidably mounted within the window frame 10, are the upper and lower window sashes 12 and 13. The parts just described are of the ordinary construction.

My latch includes a frame or supporting plate 14, which is preferably formed of a flat piece of metal having a portion bent at right angles near its upper end. The frame 14 rests against the lower window sash 13 and has the right angle extension or bent portion rest upon the upper surface of the window sash, as clearly shown in Figure 1 of the drawings. The frame 14 is secured to the window sash 13 by means of screws 15 extended through openings 16.

Secured on the right angle extension of the frame 14 is a tubular shaped member 17 having its ends bent over so as to provide end closure members 18 and 19 for the tube 17. The end closure members 18 and 19 are provided with small openings of sufficient diameter so that a plunger rod 20 may be slidably mounted therein.

The plunger rod 20 is provided with a loop 21 at its outer end. A stop member 22 is secured to the plunger rod 20 and is received within the tube 17. A coil spring 23 extends around the plunger rod 20 and is received between the closure member 19 and the stop member 22 and within the tube 17.

From the construction of the parts just described, it will be seen that the coil spring 23 tends to normally hold the stop member 22 against the closure member 18.

The frame 14 is provided with a pair of ears 24 which are provided with openings which receive the pintle rod 25. A control or actuating lever 26 is mounted for movement on the pintle rod 25 by means of a bearing cap 27. In the drawings, I have shown the bearing cap as secured to the lever 26 by means of rivets 28, but it will be understood that the lever and bearing cap may be formed of a single piece of metal with tongues or the like for engaging the pintle rod 25.

The upper end of the lever 26 is bifurcated (as at 29). The fingers on each side of the bifurcated portion 29 are bent over so as to provide loops 30. The loop 21 on the end of the plunger rod 20 is received in the bifurcated portion 29 between the loops 30. A pintle rod 31 extends through the loops 30 and through the loop 21 for connecting the lever 26 to the plunger rod 20, for forming a pivotal connection.

On the upper window sash 12, on the surface adjacent to the window sash 13, is mounted a plate 32. The plate 32 is recessed into the sash 12. The plate 30 is secured to the sash 12 by means of the screws 33. A plurality of openings 34 are provided within the plate 32 and register with openings 35 formed in the sash 12.

The free end of the plunger rod 20 is designed to be selectively received in any of the openings formed in the plate 32 and the sash 12.

In Figure 2 of the drawings, I have shown

the plunger in one of the openings and when in this position, the window sashes will be locked against movement relative to each other. When it is desired to move the window sashes relative to each other, it is necessary to release or move the plunger rod against the action of the coil spring 23 so that the plunger rod is cleared from the opening. The parts are so arranged that the plunger rod may be moved by pressing the lower end of the lever 26 inwardly or towards the frame 14.

Secured to the frame 14 just below the lower end of the lever 26 is the hand engaging element 36. The hand engaging element 36 is so positioned that it may be engaged by the four fingers of the hand, and the lower end of the lever 26 may be engaged by the thumb, wherein the plunger may be released and the lower window sash raised by engaging the hand elements.

It will be seen that the lower end of the lever is so positioned that the hand engaging element may be engaged, and the lever 25 simultaneously engaged for moving the plunger to inoperative position and raising the window sash. The plunger will move into one of the openings formed in the plate 32 due to the pressure of the spring 23.

It will be seen that my lock operates automatically and will latch the window sashes in almost any desired position. The plate 32 may be made the entire length of the upper window sash, and the openings therein 35 may be positioned as desired for securing latching positions as necessary.

My device can be used in place of cords and weights ordinarily used. The latch can be released from the inside and will then, 40 permit either the upper or lower window

sash to be raised or lowered. The latch operates from the inside and will prevent opening from the outside. Both the upper and lower window sashes will be effectively latched by the single latch structure and 45 will latch them in any desired position.

Some changes may be made in the construction and arrangement of the various parts of my invention, without departing from the real spirit and purpose of my invention and it is my intention to cover by 50 my claim, any modified forms of structure or use of mechanical equivalents, which may be reasonably included within their scope.

I claim as my invention:

In combination with windows of the sliding double sash type, means for latching one sash relative to the other, said means comprising a supporting plate secured to the upper end of a side rail of the lower 60 sash and having a right angled extension over the top of said sash, a tubular member having a restricted end mounted on said right angled extension, a plunger slidably mounted in said tubular member, a collar 65 secured to said plunger, a spring interposed between the collar and said restricted end, a lip on the other end of said tubular member for engaging the collar a perforated plate secured to the side rail of said upper sash, 70 the perforations in said perforated plate being designed to selectively coact with said plunger, a spring in said tubular member for normally holding said plunger in engagement with any one of said holes, a lever pivoted on said supporting plate for reTRACTING said plunger and a handle secured to said supporting plate adjacent the lower 75 end of said lever.

HARRY S. WHEATON.
